Cyrus N. Anderson

ATTORNEY

UNITED STATES PATENT OFFICE

HARVEY EVERETT KENDIG, OF PHILADELPHIA, PENNSYLVANIA

DRAIN DEVICE FOR SENSITIZED PLATES

Application filed January 19, 1929. Serial No. 333,569.

In the sensitizing of plates (usually if not always glass) for use in the making of photographs according to what is known as the "wet" process the said plates are placed in a solution of silver nitrate after which they are removed and allowed to drain.

Heretofore such plates have been supported in a more or less upright position with their lower ends resting upon an absorbent body of material such as blotting papers, usually a number of thicknesses thereof, the plates being allowed to remain in such position until the excess of silver nitrate solution has drained from the front faces thereof, the said solution being removed from the rear faces of the plates by wiping and cleaning the same by the use of blotting paper, cotton, rags, etc.

The chemical silver nitrate is quite expensive and it is desirable to save that which is removed from the plates, and the practice heretofore has been to preserve the blotting paper, rags or the like by which the silver nitrate has been absorbed and to extract the chemical therefrom; but the difficulty has been that such blotters, rags and the like become lost, disintegrate and for one reason or another the greater portion of the nitrate is lost, which constitutes a more or less heavy burden upon those engaged in the photographic art.

The general object of the invention is to provide a device by the use of which the silver nitrate which is or may be removed from a plate may be collected in a suitable receptacle and conveyed therefrom to a container and thereafter re-used if desired.

It also is an object of the invention to provide a device having means whereby the plates may be supported in a more or less upright position in such relation to a receptacle as to permit the excess of nitrate to drain from the front face of the said plate into the said receptacle, the nitrate upon the rear face of the said plate being removed therefrom by a suitable device and allowed to fall into the said receptacle.

A further object of the invention is to provide means whereby plates of different heights and of different widths may be read-

ily supported and sustained in proper relation to a receptacle into which the nitrate may descend from the said plates.

To these and other ends the invention comprehends the construction and arrangement of parts as hereinafter described in detail and particularly pointed out in the claims.

In order that the invention may be readily understood and its many practical advantages fully appreciated reference should be had to the accompanying drawings wherein I have illustrated one form of mechanical device embodying the said invention. It will be understood that various changes and modifications may be made in the details of construction of the said device without departing from the invention as the same is defined in the claims.

In the drawings:

Fig. 1 is a view in perspective of a device embodying the invention;

Fig. 2 is a similar view of a device which may be employed in removing the silver nitrate or other like substances from the rear side or surface of the plates;

Fig. 3 is a view in vertical longitudinal sectional elevation of the device shown in Fig. 1; and

Fig. 4 is a central transverse section of the said device.

Before proceeding with a description in detail of the device embodying my invention I desire to point out that although I have referred to the chemical silver nitrate it is to be understood that my invention is not limited in its use to the handling of plates which have been subjected to the action of a solution of silver nitrate but may be used for the handling of plates which have been subjected to the action of any other chemical in liquid form.

Referring to the drawings, I have shown a box 1 of rectangular form the upper end of which is open, as shown. The said box may be supported upon any suitable support such as a bench or the like, a portion of which is indicated at 2. A trough 3 is located within the box 1, the said trough being of angular shape in cross section, as shown in the drawings. The front edge of

the trough is provided with a forwardly extending flange 4 which extends over the top edge of the front wall of the box 1 so as to prevent the chemical which may be removed from the plates from coming in contact with the said box. The box 1 consists of wood and preferably should be painted or covered inside and outside with a coating or covering of a substance resistant to the action of silver nitrate and water or other chemical and water. The upper edges of the other side and ends of the trough may be provided with laterally extending flanges to overlie the adjoining edges of the box if desired, but in practice I have found that it is necessary only that the front edge of the box be protected, as is indicated in Fig. 1 of the drawings. The trough must consist of material which is not affected by the chemical which may come into contact therewith. The said trough may consist of a nitro-cellulose compound freed from substances which might combine with and contaminate the reclaimed silver nitrate solution, a phenolic condensation product, rubber and its combinations, or any other suitable material which is not acted upon by the chemical, whatever it may be, which may drain thereinto.

The box 1 is provided at intervals lengthwise thereof with triangular blocks 5 and 6 arranged in couples, as shown. The inner ends of the blocks of each couple overlap each other, as indicated in Fig. 4 of the drawings, and the upper edges of the blocks of each couple are arranged in angular relation to each other, the angle thereof corresponding with the angle of the opposite sides of the trough 3 to each other. That relationship is clearly shown in Fig. 4 of the drawings from which it is clear that the trough is supported upon the upper edges of the blocks 5 and 6. Instead of supporting the trough upon the said blocks 5 and 6 it may be supported by the bottom edges 45 of the ends 7 thereof resting upon the bottom of the box, the blocks 5 and 6 in that case being omitted.

The trough 3 is provided with crosswise extending bars 8 the material of which may and usually would be the same as that of the trough although that is not necessary provided the material of the said cross-bar is such that it will not be affected or acted upon by the chemical which may contact therewith. These cross-bars are provided with notches which are shown at 10, in which notches the lower ends of the plates, indicated at 11 by dash and dot lines, are located. These notches provide shoulders against which the ends of the plates may contact, and the presence of said shoulders prevents the accidental sliding outward movement of the lower ends of the plates. The upper ends of the plates rest against a suitable support which may be embodied in

the form as illustrated. The support as shown in the drawings comprises a frame which includes upright side bars 12 the lower ends of which are connected to the rear side of the box 1 while the upper ends thereof are connected to each other by means of a cross-bar 13. An intermediate upright or vertical bar 14 is provided, the said bar being located midway between the upright bars 12. The lower end of the intermediate bar is connected to the rear side of the box 1 and at its upper end to the cross-bar 13. Diagonally arranged bars 15 and 16 are provided the lower ends of which are connected to the opposite edges of the bar 14 a short distance above the upper edge of the rear side of the box 1 while the upper ends thereof are connected to the top bar 13 near its opposite ends. In addition to their function of aiding in the support of the upper ends of plates which may rest upon the cross-bars 8 the bars 15 and 16 in co-operation with the bar 14 constitute braces for strengthening and rendering more secure and rigid the frame structure as a whole which is supported upon the rear side of the box 1. For the purpose of further strengthening and rendering more secure and rigid the structure I have provided two short strips or bars 17 and 18 which are located upon the opposite sides of the lower end portion of the bar 14 below the lower ends of the diagonally arranged bars 15 and 16. The upper ends of the short bars 17 and 18 contact with and overlie the lower end portions of the diagonal bars 15 and 16. The lower ends of the short bars 17 and 18 are secured to the box 1. The bars 12, 14, 15 and 16 preferably consist of wood and in order to protect the same from the chemical upon the plates which are indicated at 11 the said bars are provided with grooves 20 within which are located narrow elongated strips 21 which consist of material which would not be affected or acted upon by any chemical which would be deposited thereon from a plate which might be supported thereagainst. The said strips 21 usually consist of the same material as that of which the trough 3 and bars 8 are made but of course the said strips may consist of any other material capable of resisting the chemical action of any chemical which might be deposited thereon from any plate which may be supported against the same. The bars 12, 13, 14, 15 and 16 may be painted or covered with a coating of substance which is resistant to the silver nitrate or other chemical which may be handled; and if so covered the strips 21 referred to may be omitted and the upper edges of the plates allowed to contact with the bars 12, 14, 15 and 16.

Likewise the trough 3 and the crossbars 8 thereof may consist of material which is not resistant to the chemical, silver nitrate, 130

or other chemical which may come in contact therewith provided they are covered with a coating of material which is resistant to such chemical; but preferably these parts

5 should consist of material which is resistant to the said chemical as hereinbefore has been described.

It will be noted that the bars 15 and 16 and the strips 21 thereon diverge upwardly

10 from the bar 14 and the strip 21 mounted thereon. It also will be noted that the strip

21 mounted upon the bar 14 extends to a point a considerable distance below the lower ends of the strips 21 upon the bars 15 and

15 16. By thus locating the strips 21 with respect to each other it will be seen that I have arranged the said strips for supporting the upper ends of plates of varying widths and heights. It may be that a relatively narrow and short plate when supported upon one or more of the bars 8 would contact only with the lower end portion of the middle strip 21, but as the plates increase in width and height it will be noted that the

20 upper ends thereof contact with all three of the strips 21 and that as the plates widen and increase in height the support for the upper ends thereof increases in width. After

25 the plates have been subjected to the action of a chemical such as silver nitrate in liquid form they are placed upon the device with their lower ends resting in the notches 10 in the upper edges of the cross-bars 8 and with their upper ends resting against and sup-

30 ported by the strips 21. While in such position the excess of chemical drains from the face of the plate which faces toward the rear of the device into the trough 3 while by means of a wiping device 25 the said

35 chemical is removed from the rear face of the plate, such face being that which faces toward the front of the device as illustrated. The chemical which drains from one of the faces of the plates and that which is re-

40 moved or which may drain from the other faces of said plates descends or falls into the trough 3 and flows therefrom through a short pipe 26 mounted in an opening pro-

45 vided in one end of the trough 3. Prefer-

50 ably the trough should be inclined toward the end upon which the pipe 26 is mounted so as to facilitate the flow of the silver nitrate or other chemical solution to the said pipe.

A flexible pipe extension 27 is connected at

55 one end to the outer end of said pipe and its opposite end projects into a bottle 28 or other container into which the chemical is discharged from the said trough. The pipe

26 and the flexible pipe extension 27 must

60 be chemically resistant to the solution of silver nitrate or other chemical being handled.

It will be noted that the sides of the trough

65 meet at an angle so that the chemical, which is in liquid form, gathers in the angle be-

tween the sides at the bottom of the trough, its outflow being thereby facilitated. From time to time if desired water may be poured into the trough to wash therefrom the chemical such as silver nitrate.

The chemical; for example, silver nitrate, 70 collected in the bottle 28 may be strained or filtered and thereafter again used as an agent for sensitizing photographic plates, for intensifying or for any purpose in photography for which silver nitrate in solution is 75 desirable.

The wiper 25 previously referred to consists of a body portion of material resistant to silver nitrate and other chemical substances which may be reclaimed within one edge of which a flexible wiping element is provided which may consist of rubber or other material chemically resistant to silver nitrate or other chemical which may be handled. Wiping devices of the character illustrated are well known and in general use for 80 similar purposes.

It will be seen that by my invention I have provided a device simple in character but very efficient for the purpose for which it is intended; namely, collecting and saving of a liquid chemical; for example, silver nitrate, which may drain or otherwise be removed from the surfaces of sensitized plates, usually glass, which may be used in the photographic or other art.

Having thus described my invention, what I claim and desire to secure by Letters Patent is:

1. A device of the character described comprising a trough having bars extending transversely of the open top thereof, means for supporting said trough, and means outside of said trough co-operating with said bars to support a plate in an upright position, the lower end of said plate being supported upon the said bars over the said trough.

2. A device of the character described comprising a trough the opposite sides of which are plane and meet each other to form an angle, an open topped box within which the said trough is located, and means for supporting a plate in an upright position with its lower end located over the said trough.

3. A device of the character described comprising a trough consisting of material resistant to chemical substances, the opposite sides of said trough being arranged in angular relation to each other and the said trough being provided with a port through one end adjacent the bottom of the said trough, means for supporting the said trough, cross-bars supported in spaced relation to each other upon the upper edge portions of the opposite sides of the said trough, upright bars mounted upon the rear side of the support for the said trough, the said bars being provided with strips of material of a substance resistant to chemical action, the said

cross-bars and the strips upon the said upright bars co-operating to support a plate in upright position.

4. A device of the character described comprising an open topped box having transversely extending blocks mounted therein, the upper edges of which are inclined downwardly and inwardly in opposite directions in angular relation to each other, a trough consisting of material which is not affected by chemical substances which may come into contact therewith, the said trough being located in the angles formed by the blocks in the said box and being supported by the said blocks, cross-bars supported upon the upper edge portions of the said trough, and upright supporting means mounted upon the said box and co-operating with the said cross-bars to support plates in upright positions.

20 5. A device of the character described comprising a trough having cross-bars supported upon the upper edge portions of the opposite sides thereof, the said trough and cross-bars consisting of material which will not be affected by silver nitrate should the latter come into contact therewith, a support for the said trough, upright bars mounted upon said support, the said bars having strips of material mounted thereon and projecting from the front sides thereof consisting of material which will not be acted upon by silver nitrate should the latter come into contact therewith, the said bars and the said strips being adapted to support plates in upright position.

6. A device of the character described comprising an open topped box having blocks mounted therein and extending transversely thereof, the upper edges of the said blocks being inclined inwardly and downwardly, a trough located within the said box and supported upon the upper edges of the said blocks, said trough being provided with a port in one end thereof and also being provided with cross-bars supported upon the upper edge portions of the opposite sides thereof, the said trough and cross-bars consisting of a material capable of resisting the chemical action of silver nitrate, a vertically extending bar mounted upon the said rectangular box, and bars connected at their lower ends to the opposite edges of the said vertical bar at points located a distance above the upper edge of the rear side of the said box, the said last mentioned bars extending upwardly and in divergent relation with respect to the first named bar and each of the said bars being provided with a narrow strip mounted in a groove provided therein, each 60 of the said strips projecting beyond the surface of the side of the bar in which it is located, the cross-bars mounted upon the said trough and the said vertical bar and bars extending divergently upwardly from the said vertical bar co-operating to support plates

with the lower ends thereof located over the said trough.

7. A device of the character described comprising an open topped box, a trough consisting of a phenolic condensation product, said trough having cross-bars of the same material supported at their opposite ends upon the upper edge portions of the opposite sides of the said trough, means within the said box for supporting said trough, and bars mounted upon the rear side of the said box and extending upwardly, the said bars and the bars which extend crosswise of the said trough co-operating to support a plate in upright position, with the lower end of said plate located over the said trough.

8. In combination, a trough comprising material resistant to silver nitrate in solution, bars mounted upon said trough and extending crosswise thereof, and means for supporting a plate in upright position with its lower end resting upon said bars whereby liquid substance which may drain from either or both faces of the said plate will descend into the said trough, said means tapering from its upper toward its lower end.

In testimony that I claim the foregoing as my invention I have hereunto signed my name this 17th day of January, A. D., 1929.

HARVEY EVERETT KENDIG.
